ing in the forward end thereof, radially adjustable supporting devices for mounting said motor casing, a rotary steam motor in said casing, means to direct the exhaust steam from said motor into the conveyer, a fan secured to the motor shaft and adapted to drive air inward around the motor casing and into the conveyer.

4. In a fan blower a conveyer, a motor casing in the forward end thereof, means for centering said motor casing in the conveyer, means for directing the exhaust steam from said motor through the exhaust head in the motor casing, a converging delivering funnel secured to said inner end of the motor casing and projecting into the conveyer, a fan on the motor shaft in front of the motor casing and larger in diameter than said motor and adapted to drive air inward around the motor and out-side of the delivering funnel.

5. In a fan blower a conveyer, a motor casing mounted in the forward end thereof, radially adjustable devices for centering said motor frame, a motor shaft, adjustable centering points for the ends of said shaft, a rotary steam motor wheel within the motor

casing and secured to said shaft, means for directing the exhaust from said motor casing through the inner exhaust head thereof, an inwardly tapering funnel to receive said exhaust and direct it to the center of the conveyer, a fan on the outer end of the motor shaft and larger in diameter than the motor casing and arranged to draw air inward around the motor frame. 30

6. In a fan blower a tubular conveyer, a rotary steam motor mounted in the forward end thereof, a fan operated by said motor and adapted to draw air inward around the motor frame, a perforated steam ring arranged in the conveyer and adapted to direct steam inward on inclined lines, and means for simultaneously delivering steam to the motor and to the ring. 40

In testimony whereof I hereunto affix my signature in the presence of two witnesses this 30th day of November 1906.

UNITED STATES PATENT OFFICE.

GEORGE E. R. ROTHENBUCHER, OF NEW YORK, N. Y.

SMOKE-CONSUMING FURNACE.

No. 872,374.

Specification of Letters Patent.

Patented Dec. 3, 1907.

Application filed March 12, 1907. Serial No. 362,048.

To all whom it may concern:

Be it known that I, GEORGE E. R. ROTHENBUCHER, a citizen of the United States, residing in the borough of Brooklyn, county of 5 Kings, city and State of New York, have invented certain new and useful Improvements in Smoke-Consuming Furnaces, of which the following is a specification, reference being had therein to the accompanying drawings, 10 in which—

Figure 1 is a horizontal sectional view of a furnace provided with my invention; and Fig. 2 a transverse vertical sectional view thereof.

15 The main object of the invention is to provide an improved furnace in which cheap fuel, such as shavings and refuse from saw mills, soft coal, &c., will be entirely consumed within the fire box, or combustion 20 chamber, thereby preventing the escape of carbon particles in the form of smoke.

Another object of the invention is to provide means whereby exhaust steam and air may be delivered under a suitable pressure, 25 and in the proper direction, over the fire in the fire box and upward through the bridge wall to promote complete combustion.

A further object of the invention is to provide means whereby a part of the smoke will 30 be withdrawn from the fire box near the forward end thereof into side flues and there mixed with air, or air and steam, and then passed into the fire box near the rear end thereof and through the bridge wall.

35 Other objects of the invention, relating more particularly to details of construction, will be fully hereinafter described and particularly pointed out in the claims.

Referring to the various parts by numerals, 1 designates the boiler front, 2 the fire box and 3 the bridge wall. In the side walls 40 of the furnace, a suitable distance above the grate 4, are steam and air flues 5, one of said flues being in each wall and extending the 45 full length of the fire box, parallel with the side walls thereof. Each of these flues is formed of three interlocked cast iron tubular sections or boxes 6, 6 and 6^a which open into each other and whose inner surfaces are 50 flush with the inner surface of the side wall of the furnace. On the inner faces of these tubular sections 6, 6 are formed heating and deflector walls 7 which incline inward and rearward at an angle of forty-five degrees 55 with respect to the side wall of the furnace. Each section 6 is formed with slits or open-

ings 8 which extend inward through the wall of the section from the inner end of the deflector wall 7 and at the same angle as said deflector wall. The result of this is that thin 60 vertical streams of mixed steam and air flow outward through said slits over the deflector walls and into the fire box. The deflector walls form the forward sides of angular projections on the face of the sections 6, said 65 projections being V-shaped in plan view. As these projections extend into the fire box it will be readily seen that they become highly heated and that the deflector walls serve as 70 heating surfaces for the mixed steam and air.

The sections 6^a are formed with slits or openings 8^a which extend horizontally outwardly and rearwardly on an angle of about forty-five degrees with respect to the inner face of said sections 6^a. Within the sections 75 6^a these slits or openings 8^a are continued through nozzle-like projections 8^b which extend a suitable distance within the section 6^a and incline rearwardly as shown in Fig. 1. The purpose of this will clearly appear here- 80 inafter.

The bridge wall 3 is formed at its upper edge with a cellular structure having horizontal passages 9, said passages being formed by suitable brick work. In the bridge wall 85 along the base of these passages is arranged a transverse flue or pipe 10 which connects at its ends with the rear ends of the side flues 5. The flue 10 is very much smaller in capacity than the flues 5 and is connected to these latter flues near the bottoms thereof. The object of this is to hold the larger proportion of steam and air in the flue 5 and to permit only a small portion thereof to pass into the flue 10. This latter flue or pipe is perforated, 95 said perforations opening into the passages 9 so that the steam and air will be directed into said passages to there mingle with the flame and products of combustion from the fire box. It will be readily understood that the 100 pipe 10 will become highly heated and will thereby act as a superheater to the mixed air and steam, and that said mixture will pass into the passages 9 in a very dry condition and will assist greatly in promoting combus- 105 tion.

To supply air and steam to the forward ends of the flues 5 I provide for each flue a tubular conveyer 11. Any suitable means may be employed for forcing the steam and air through said conveyers, but I prefer to use the means shown in my co-pending appli- 110
